(57) **CLAIM**

The ornamental design of an aspiration detector, as shown and described.

DESCRIPTION

FIG. 1 is a front isometric view of the aspiration detector with a front door of the aspiration detector in an open position.

FIG. 2 is a front view of the aspiration detector with the front door of the aspiration detector in the open position.

FIG. 3 is the front view of the aspiration detector with the front door of the aspiration detector in a closed position.

FIG. 4 is a left side view of the aspiration detector with the front door of the aspiration detector in the open position.

FIG. 5 is a right side view of the aspiration detector with the front door of the aspiration detector in the open position.

FIG. 6 is the left side view of the aspiration detector with the front door of the aspiration detector in the closed position.

FIG. 7 is the right side view of the aspiration detector with the front door of the aspiration detector in the closed position.

FIG. 8 is a top view of the aspiration detector with the front door of the aspiration detector in the open position.

FIG. 9 is the top view of the aspiration detector with the front door of the aspiration detector in the closed position.

FIG. 10 is a bottom view of the aspiration detector with the front door of the aspiration detector in the open position; and,

FIG. 11 is the bottom view of the aspiration detector with the front door of the aspiration detector in the closed position.

Rear views of the aspiration detector are intentionally omitted and do not comprise additional features of the claimed design. In the drawings, the broken lines are for the purpose of illustrating environment only and form no part of the claimed design.

1 Claim, 8 Drawing Sheets
